IRA KINMAN, OF FREEPORT, ASSIGNOR TO SARAH KINMAN, OF STEPHENSON COUNTY, ILLINOIS.

Letters Patent No. 77,890, dated May 12, 1868.

IMPROVED CURTAIN-FIXTURE.

The Schedule referred to in these Letters Patent and making part of the same.

TO ALL WHOM IT MAY CONCERN:

Be it known that I, IRA KINMAN, of Freeport, in the county of Stephenson, and in the State of Illinois, have invented certain new and useful Improvements in Roller for Window-Curtains; and do hereby declare that the following is a full, clear, and exact description thereof, reference being had to the accompanying drawings and the letters of reference marked thereon:

In the annexed drawings, making a part of this specification—

A represents a suitable frame, constructed as shown in the drawings, and which forms suitable bearings for the roller B to work and rest in.

C represents a curtain, used either for windows or for a stage-curtain, and is secured to its roller in any suitable manner, and has a slat, D, fastened to its lower end, as shown.

Upon one end of the roller B, I secure a crank, h, by which said roller is turned or revolved, and the curtain thereby elevated.

The crank h passes through the roller B, and turns therein, so as to hook or catch over the lip or catch g in the frame A.

The curtain is elevated or wound up as high as desired by means of the crank h, which is then turned in its socket in the roller B, and caught over the hook g, as above described.

The slat or strip D has rings or loops, j, adjusted or inserted to its lower side, to provide a convenient means of pulling down or lowering the curtain C when the crank h is detached from the hook g. Said crank h makes a secure fastening for the curtain C, as will be seen.

Having thus fully described my invention, what I claim as new, and desire to secure by Letters Patent, is—

The reversible crank-handle h and angular catch g, in combination with the roller B, and arranged to operate as set forth.

In testimony that I claim the foregoing, I have hereunto set my hand, this 22d day of February, 1868.

IRA KINMAN.
